BURR REMOVING MACHINE

Hugh Whitman Haynes, Joliet, Ill., assignor to
The American Steel and Wire Company of
New Jersey, a corporation of New Jersey

Application October 7, 1937, Serial No. 167,843

4 Claims. (Cl. 90—44)

The present invention relates to an apparatus for removing burrs from welded rod ends, rings or loops.

One object of the invention is to provide an apparatus which will remove the burrs from the entire circumference of the metal without the necessity of taking the metal out of the apparatus and turning it around.

Another object is to provide a holding and clamping device on the apparatus for relieving the operator from holding the burr against the cutter, and permits him to rotate the metal in a more uniform manner, resulting in a more uniform removal of the burr.

Other objects and advantages will become apparent as the description proceeds, in which:

Figure 1 is a vertical sectional elevation of the apparatus of the present invention;

Figure 2 is a sectional elevation at right angles to Figure 1;

Figure 3 is an enlarged detailed view showing the jaws, cutters, metal supporting member and the means for rotatably holding the metal on the supporting member; and,

Figure 4 is a top plan of the construction shown in Figure 3.

In the drawings, the numeral 2 represents a welded steel frame for supporting and housing the operating mechanism of the present invention.

Extending into said frame from a motor is a shaft 3 adapted for eccentric movement. Suitably journaled upon said shaft is an arm 4 to which is pivotally connected the reciprocating jaw member 5. A reciprocating jaw member 6 is provided with a laterally extending arm 7 for pivotally connecting, for simultaneous vertical movement, said members 5 and 6.

The reciprocating member 5 is slidably supported in a bracket arm 8 secured, in any conventional manner, to said frame 2. Adjacent the upper end of each of the members 5 and 6, there is provided a cut-out portion for receiving the cutters 9.

Mounted upon the top of said frame 2, in any conventional manner, is a rod supporting member 12, of substantial U-shaped construction and provided with a slot 14 through which bolts 15 are adapted to pass. This supporting member 12 is capable of being adjusted transversely of the vertical plane of the metal rods 16 and is provided, on the upper surface of one end, with a tapered portion 17 which supports said metal rods 16 thereon.

Also mounted upon the top of said frame 2, in

any conventional manner, are guide blocks 18 and 19 having suitable openings through which is adapted to slide, transversely of the vertical plane of the metal rods, a rod holding member 20 of substantially U-shaped construction provided with an integrally formed laterally extending arm 21. Pivotally secured to said member 20, at 22, is a bell-crank 23. The bell-crank is pivotally supported on the frame at 24 and has pivotally secured, at 25, to the other arm thereof the treadle operated lever 26.

A bracket 27 is secured to said frame, in any conventional manner, and pivotally supports a bell-crank 28 on one end of which is mounted the roller 29 while the other end is slidably connected, through the pin and slot construction shown at 30—31, to said treadle operated lever 26. A spring 32 normally maintains the treadle 33 in the position shown by dotted lines in Figure 1.

In operative position, the foot treadle 33 being in raised position as shown in dotted lines of Figure 1, the rod holding member 20 is in its retracted position and the hinged jaw member 6 is in the dotted line position shown in Figure 3. This permits insertion of the burred rod or hoop 16 upon the adjustable supporting member 12, after which pressure is applied to the treadle 33 which moves the rod holding member 20 in a direction transversely of the vertical plane of the rod or hoop 16, so as to rest upon the top of said rod or hoop and rotatively hold the same on the supporting member 12. Upon further pressure on the foot treadle 33, which results in a further upward movement of the lever 26, the pin 30 engages the bottom of the slot 31 on said lever and causes an upward movement of the arm of the bell-crank 28; and, due to its pivotal connection on the bracket 27, the other arm carrying the roller engages the pivotally movable jaw member 6 to force the same inwardly in order that the cutter may engage the burred portion of said rod or hoop for removing said burred portion upon reciprocation of the jaw members 5 and 6. Such a construction requires no effort on the part of the operator to hold the burred portion of the rod or hoop against the cutters. It permits him to rotate the hoop, as shown in dotted lines in Figures 1 and 3, in a more uniform manner, resulting in a more uniform removal of the burr from the material without the necessity of taking the rod or hoop out of the apparatus and turning it around in order to remove the burred portion from the entire circumference of the material.

While I have shown and described a specific

embodiment of the present invention, it will be seen that I do not wish to be limited exactly thereto, since various modifications and changes may be made without departing from the scope 5 of the invention, as defined by the following claims.

I claim:

1. An apparatus for removing burrs from 10 welded rod ends including a pair of spaced oppositely disposed pivotally connected reciprocating members, cutters on said reciprocating members, a rod supporting member, a U-shaped member for rotatably holding said burred welded rod on said supporting member with the burr in the 15 path of said cutters and means for reciprocating said cutters.

2. An apparatus for removing burrs from 20 welded rod ends including a pair of spaced pivotally connected reciprocating members, cutters on 25 said reciprocating members, an adjustable rod supporting member having an inclined upper face, means for holding said burred welded rod for rotatable movement on said inclined face of said supporting member and means for reciprocating said cutters.

3. An apparatus for removing burrs from

welded rod ends in a single operation including a 5 pair of pivotally connected reciprocating members, cutters on said reciprocating members, a transversely adjustable rod supporting member, a U-shaped member for holding said burred welded rod for rotatable movement on said supporting member with the burr in the path of said cutters and means for reciprocating said cutters in unison, said holding means adapted to be moved transversely of the vertical plane of said rod. 10

4. An apparatus for removing burrs from 15 welded metal in a single operation including a pair of spaced reciprocating members, cutters on said reciprocating members, one of said reciprocating members pivoted to the other reciprocating member to provide an adjustment for different diameters of burred metal, an adjustable supporting member, a transversely movable member for rotatably holding said burred metal on 20 said supporting member in the path of said cutters, means for applying pressure to said reciprocating members to maintain said cutters against said metal, and means for reciprocating said members. 15

HUGH WHITMAN HAYNES. 25
